UNITED STATES PATENT OFFICE.

MARK DAVIS, OF NEW YORK, N. Y.

DESIGN FOR A CAP.

SPECIFICATION forming part of Design No. 31,107, dated June 27, 1899.

Application filed May 3, 1899. Serial No. 715,482. Term of patent 34 years.

To all whom it may concern:

Be it known that I, MARK DAVIS, a citizen of the United States, residing at the city of New York, borough of Manhattan, in the county 5 and State of New York, have invented and produced a new and original Design for a Cap, of which the following is a specification, reference being had to the accompanying drawing, forming a part thereof, in which the figure is a perspective view of a cap embodying 10 the features of my design.

The leading feature of my design consists in the oppositely-inclined vizors A and B and a crown C, supported by the vizors, the top 15 of the crown being approximately flat and the sides thereof bulging down over the vizors and appearing to curl inward at the vizors.

The minor features of the design consist in a button-like ornament 10 at the central portion of the crown and ribs 11 extending 20 from the margin of the crown to its button ornament 10. The vizors are at opposite ends of the crown and apparently meet at the sides of the crown.

I claim—

The design for the cap herein shown and described. 25

MARK DAVIS.
